UNITED STATES PATENT OFFICE.

HARRY G. GEISSINGER, OF DETROIT, MICHIGAN, ASSIGNOR TO VAPOR CAR HEATING COMPANY, INC., OF CHICAGO, ILLINOIS, A CORPORATION OF NEW YORK.

CAR-HEATING SYSTEM.

Original application filed September 9, 1918, Serial No. 253,323. Divided and this application filed May 1, 1922. Serial No. 557,534.

To all whom it may concern:

Be it known that I, HARRY G. GEISSINGER, a citizen of the United States, residing at Detroit, in the county of Wayne and State of Michigan, have invented certain new and useful Improvements in Car-Heating Systems, of which the following is a specification.

My invention relates to apparatus for controlling the operation of a heating system, more particularly, a steam heating system adapted for railway cars.

The primary object of the invention is to provide a heating system in which the amount of heat delivered to the car will depend upon two factors: first, upon the amount of active radiation surface, which, in accordance with my invention, may be varied; and, second, upon the amount of heating medium circulated through the radiator, which I propose to regulate by means of thermostatic mechanism located in the car.

The invention contemplates a radiator in the car consisting of a plurality of coils, or other radiating units adapted to be put into and out of operation separately so that the capacity of the system may be varied. The actual amount of heating medium passing through the coil or coils in service will depend upon the amount required for maintaining the car temperature at the point desired. Whether the car be heated to maintain a relatively high temperature (normal temperature of occupancy) or a lower temperature (night time temperature, in the case of sleeping cars, or still lower temperature when the car is standing empty in the yard or terminal) depends upon whether the thermostatic mechanism in the car is set for the high temperature or for one of the lower temperatures.

In connection with the division of the radiator into a plurality of separately operable units a feature of the invention is that while one of the units may be closed against inflow of heating medium it cannot be reopened without becoming subject to the controlling mechanisms which govern the system as a whole.

A further object of the invention is to apply the controlling devices and arrange-

ments, as above outlined, to the control of a vapor heating system in which a vapor regulator is employed for preventing the passing of steam through the coil or coils in service in an amount in excess of the capacity of such coil or coils to condense the same.

The invention consists in the new and improved arrangements, devices and constructions to be hereinafter described and claimed for carrying out the foregoing objects and such other incidental objects as will appear from the following description of the preferred embodiment of the invention illustrated in the accompanying drawings.

The present application is a division of my co-pending application Serial No. 253,323 for automatically controlled car heating system, filed September 9, 1918.

In the drawings,

Fig. 1 is a diagram illustrating the heating system of my invention, as a whole, in a preferred embodiment.

Fig. 2 is a vertical sectional view of the vapor regulator constituting a part of the mechanism for controlling the circulation of steam through the radiator.

Fig. 3 is a fragmentary sectional view, somewhat diagrammatic in character, the right hand end of which shows the apparatus in vertical sectional elevation and the left hand end in plan, with parts in section, and

Fig. 4 is a view of the valve illustrated in Figs. 1 and 3 for shutting off steam to one of the radiators, the valve being shown in a different position from that indicated in Fig. 3.

Referring to the drawings, A designates the steam train pipe of a railway car, and B and C two radiating coils which are located in the car and may be termed the primary and auxiliary coils or units, respectively, of the car radiator. By primary coil I mean the coil or radiator element which receives steam whenever steam is circulated through the radiator. By auxiliary coil I mean a coil which may or may not receive steam when the primary coil is supplied. D is a vapor regulator. E is a four-way valve for controlling the circulation of the heating medium through the primary coil

B, and F a similar valve for controlling the circulation of medium through the auxiliary coil C. These valves preferably stand open under normal conditions, and are closed by the operation of the air motors G and H. Compressed air for actuating these motors is taken from the air train line J which may form part of the air brake system of the car and its application to the motors is controlled by a magnetically actuated air valve K. L is what may be termed a radiation valve which is adapted, in one position, to bring about the closing of the four-way valve F of the auxiliary coil C and, in its other position, to subject this valve to control by the air valve K which latter, in the preferred embodiment of my invention shown, at all times controls valve E of the primary coil B.

The air valve K is governed in its movements, automatically, by a thermostatic mechanism located in the car, which is adapted to be set so as to maintain the car atmosphere either at the normal living temperature or at a lower temperature or temperatures. This mechanism consists, in the form of the invention shown, of three thermostats M, N and O, any one of which may be made effective, at will, to the exclusion of the other two, by operation of a switch P. In the arrangement shown thermostat M, when in control, maintains the car temperature at the normal temperature of occupancy, for example 70° Fahrenheit, and is termed the high temperature thermostat. The thermostat N, which may be termed the medium temperature thermostat, is intended to control the heating system during the night hours while the car is occupied and may be set to maintain a temperature of 60° Fahrenheit, for example. The thermostat O, which is termed the low temperature thermostat, is set to operate preferably at a considerably lower temperature, for instance at 50° Fahrenheit, and is intended to control the heating system when the car is standing unoccupied in a railway yard or at a terminal. During such periods it is necessary to keep the car only at such temperature as will prevent the freezing of water pipes and fixtures and injury to the finish of the car; and inasmuch as the ordinary passenger car is out of service on the average for considerably more time than it is in service, an important saving in fuel results from this reduction of temperature maintained while the car is standing empty. The switch P is indicated as a hand operated switch but any suitable mechanism might be employed for controlling its selection of the car thermostats M, N and O.

Referring now more particularly to Figs. 3 and 4, the casing of the four-way valve E is divided into four chambers 25, 26, 27

and 28. These chambers are put into communication with each other in pairs by the revoluble valve member 29 which is shown as provided with an operating lever 30. The lever 30 is connected with the piston 31 of the air motor G by connecting rod 32. 33 is a spring which exerts tension on a lever 34 having a slot and pin connection with rod 32. In the normal position of the parts of the apparatus the valve member 29 stands in its open position under the action of spring 33, that is to say, in the position shown in Fig. 3 of the drawings. The valve is closed by the movement of piston 31 when air motor G is subject to air pressure. The inlet pipe 35 of the primary coil B leads from chamber 26. The return pipe 36 of the primary coil discharges into chamber 27.

The four-way valve F for the auxiliary coil C and the air motor H for operating this valve are preferably of the same construction as the corresponding devices used in connection with the primary coil B and in the drawings the parts are given corresponding reference numerals distinguished by the exponent letter a.

Chamber 25^a of four-way valve F is connected by a pipe 37 with the chamber 28. The inlet pipe 38 of auxiliary coil C leads from chamber 26^a of valve F and the return pipe 39 of the auxiliary coil discharges into chamber 27^a. 40 is a pipe which leads from chamber 28^a of valve F to the thermostat chamber of the vapor regulator D. 41 is a pipe leading from the low pressure chamber of the vapor regulator to chamber 25 of valve E.

The construction of the vapor regulator is shown in Fig. 2 and is as follows: 42 is a casing in which is a high pressure chamber 43 connected by pipe 44 (Fig. 1) with the steam train pipe A, and a low pressure chamber 45 from which leads pipe 41 just mentioned, the chambers being connected by a port 46 controlled by a valve 47, the stem 48 of which is pivoted to a bell crank 49 to the other end of which is connected a stem 50 bearing on a thermostatic element 51 arranged in a tubular casing 52 connected by web 53 with casing 42. Pipe 40 is tapped into casing 52. The space within casing 52, designated 54, may be termed the thermostat chamber of the vapor regulator.

The magnetic air valve as shown herein, and particularly in Fig. 3, is preferably constructed as follows: It comprises a casing 55 which is formed to provide a cylinder 56 of relatively small diameter and a cylinder 57 of larger diameter. In these cylinders operates a double piston valve member 58 having a piston 59 to fit the larger cylinder and a piston 60 to fit the smaller cylinder. The casing 55 is also provided with a magnet chamber 61 in which

is located an electro-magnet 62 having a pivoted armature 63 connected with a double valve 64 which, when the magnet is deenergized, is adapted to close an exhaust port 65, and when the magnet is energized, to close a port 66 between chamber 61 and the lower end of cylinder 56. The latter is formed at its upper end with a port to the atmosphere, designated 67, and the upper end of cylinder 57 is connected by a pipe 68 with the magnet chamber 61. 69 is a pipe leading from the air train line J to a pipe 70, one end of which communicates with a duct 70^a leading to port 66 in the magnetic valve device K, the other end of which extends to and is tapped into the casing 71 of the radiation valve L. 72 is a pipe leading from cylinder 56 of the magnetic valve device K to air motor G, 73 a pipe between pipe 72 and the radiation valve L, and 74 a pipe aligned with pipe 73 and connecting the radiation valve with air motor H. The radiation valve is a three-way cock provided with a revoluble valve member 75 formed with a through port 76 and a branch port 77 at right angles thereto. The valve member is revoluble through an angle of 90° and is provided with a handle 78 for turning it.

30 The thermostats M, N and O (referring now to Fig. 1) are preferably of like construction. Any suitable form of thermostat might be employed. I have indicated thermostats of the arc and chord type which break the circuits which they control at rise of temperature. That is to say, the thermostat is composed, in each case, of a chord member 79 of major expansibility, and an arc or circuit breaking member 80 of lesser expansibility.

I do not claim herein, generically, the arrangement in the car of three thermostats (or equivalent thermostatic mechanism) adapted to be set, selectively, for the maintenance in the car of any one of three temperatures as this feature of the apparatus herein disclosed is claimed in my co-pending application above referred to.

50 The operation of the apparatus above described is as follows: In the drawings the parts of the apparatus are shown in the position which they assume when the car is subject to control by the medium temperature thermostat N and is at a temperature below that at which this thermostat operates to break its circuit. The radiating coils are, therefore, open and receiving steam. The car temperature, it will be assumed is above that for which the low temperature O is set so that the arc member 80 of this thermostat is out of contact with point 81 against which it is adapted to bear. Thermostats M and N are both in the circuit closing positions, that is to say, with 55 their arc members 80 in contact with the

contact points 82 and 83, respectively. However, the high temperature circuit is open at the selector switch P. This switch is on contact 84 closing a circuit through the medium temperature thermostat N as follows: (circuit No. 1) battery 85, wire 86, switch P, contact 84, wire 87, contact point 82, thermostat N, wire 88, wire 89, resistance 90 and wire 91 to battery. 70

The magnet 62 is on a shunt from the 75 circuit above described, the magnet circuit being as follows: (circuit No. 2) battery 85, wire 86, wire 92, magnet 62, wire 93, wire 89, resistance 90, wire 91, battery 85.

The resistance through circuit No. 2 is 89 greater than the resistance of circuit No. 1 so that so long as circuit No. 1, through the thermostat N, remains unbroken magnet 62 will not receive enough current to attract its armature 63. The compressed air from pipe J will, therefore, pass through pipes 69, 70 and ports 70^a, 66 into the magnet chamber 61 and through pipe 68 into the cylinder 57. The pressure against piston 59 of the double valve 58 will overbalance 95 the pressure exerted against piston 60 of this valve and the valve will be held in its lower position, as shown in Fig. 3. Therefore no air will pass to the air motor G nor, assuming that the radiation valve is 100 in the position shown in Fig. 3, will any air pressure be exerted upon the air motor H. The four-way valves E and F will stand open and steam from the train pipe, reduced to substantially atmospheric pressure by vapor regulator D, will pass first through the primary coil B and then through the auxiliary coil C. Water of condensation from the radiators outflows through the pipe 40. Any excess of steam 105 in the coils will result in discharge of the excess into the thermostat chamber 54 of the vapor regulator and thermostatic member 51 will be expanded so as to close, or throttle the port between high pressure 110 chamber 43 of the vapor regulator and the low pressure chamber 45.

As soon as the temperature of the car reaches that for which thermostat N is set, the circuit through this thermostat is broken 115 (circuit No. 1) and magnet 62 is energized, attracting its armature 63 and causing valve 64 to be raised to open exhaust port 65 and close port 66. Pressure in the magnet chamber 61 and cylinder 57 is relieved, the double 120 piston valve 58 raised, and the air pressure flows from pipe 70 through ports 70^a, 66, and cylinder 56 into pipe 72 and thence to the air motor G which is operated to close the four-way valve E, moving valve member 125 29 thereof from the position shown in Fig. 3 to a position at right angles thereto. At the same time air flows through pipe 73, radiation valve L and pipe 74 to the air motor H operating the same to close the 130

four-way valve F of the auxiliary coil. Steam now passes from pipe 41 through chambers 25 and 28 of valve E, pipe 37, chambers 25^a, 28^a of valve F, and out through pipe 40 to the vapor regulator which throttles down inflow so that just enough steam is circulated to keep the vapor regulator and associated parts from freezing.

It will be assumed now that the car is cut off from the locomotive and taken to a railroad yard where its steam train pipe is connected with the yard steam supply pipe. The selector switch P is moved to the left (Fig. 1) upon contact 94, closing a circuit 10 through the low temperature thermostat as follows: (circuit No. 3) battery 85, wire 86, switch P, contact 94, wire 95, contact point 81, low temperature thermostat O, wire 96 to wire 89, and thence by circuit No. 1 to the battery. If this circuit is closed at thermostat O the magnet 62 is inactive and steam circulates through the radiating coils as above described. If the circuit is open at the thermostat magnet 62 is energized to 20 close valves E and F so as to short circuit the radiating coils.

For maintaining the car atmosphere at the normal temperature of occupancy, the selector switch P is moved to the right (Fig. 30) 1) upon contact 97, closing a circuit through the high temperature thermostat as follows: (circuit No. 4) battery 85, wire 86, selector switch P, contact 97, wire 98, high temperature thermostat M, wire 99 to wire 89 and thence by circuit No. 1 to the battery.

If this circuit is closed at thermostat M the radiating coils are supplied with steam. When the circuit is broken at the thermostat magnet 62 is energized to bring 40 about the closing of valves E and F and the short circuiting of the radiator coils.

A description of the operation of the apparatus, as given above, assumes that the radiator is active as a whole, that is to say, 45 in the particular embodiment shown that both radiator coils are either open or closed. If it is desired to decrease the heating capacity of the system, which decrease will have the advantage of shortening the course 50 through which the steam and water of condensation must flow, this can be done by shifting the revoluble member 75 of radiation valve L from the position shown in Fig. 3 to that shown in Fig. 4. In the latter 55 position of the radiation valve the air pressure is applied directly to the air motor H of the auxiliary coil through pipe 70, the radiation valve L and pipe 74, as a result of which the air motor H of the auxiliary coil 60 is at all times subject to the air pressure regardless of the movements of the electrically controlled valve 64. The air motor G controlling the valve E of the primary coil B will remain subject to control through movements of valve 64, that is to say, subject to

the control of thermostats M, N or O, as the case may be. As soon, however, as the radiation valve is returned to its normal position (Fig. 3) the auxiliary coil is again placed under the automatic control of the 70 thermostatic mechanism governing the valve of the primary coil. In other words, the apparatus is capable of manual manipulation to cut out a part of the radiating surface of the radiator but whenever this part of the 75 radiating surface is active it is necessarily under the control of the thermostat or thermostats which govern the circulation of medium through the rest of the system.

It will be apparent that the multiple temperature regulation, which is a preferred feature of my apparatus, might be employed in connection with a single radiator; and that, conversely, the multiple coil system shown might be employed in connection with 85 a thermostatic mechanism functioning at one temperature only. Furthermore, modifications in the construction and arrangement of the parts of the apparatus will suggest themselves to those skilled in this art. 90 I wish it to be understood, therefore, that my invention is to be regarded as including all modified arrangements coming within the scope of the appended claims.

I claim:

1. A car heating system comprising, in combination, primary and secondary units, the latter of which is adapted to receive heating medium from the former, said units being provided severally with valves to govern the supply of heating medium thereto, thermostatically actuated mechanism for operating said valves to control the amount of heat delivered to the car, and means whereby one of said valves may be closed independently of said thermostatic mechanism but which permits the opening of the valve only under control of said mechanism.

2. A car heating system comprising, in combination, primary and secondary radiating units, the latter of which is adapted to receive heating medium from the former, thermostatically actuated mechanism subject to temperature changes in the car for controlling the introduction of heating medium into said units, and means whereby one of said radiating units may be closed and freed from control of said thermostatic mechanism but when re-opened is put under the control thereof.

3. A car heating system comprising, in combination, primary and secondary radiating units, the latter of which is adapted to receive heating medium from the former, said units being provided severally with valves to govern the supply of heating medium thereto which normally stand open, thermostatically actuated mechanism which at a given temperature operates to close said valves, and means for closing one of said

valves independently of said mechanism, which means permits the opening of the valve only under the control of said mechanism.

4. The combination with a railway car provided with a source of supply of air under pressure, of a heating system comprising a plurality of radiating units, pressure actuated means for closing said units against the admission of heating medium, thermostatic mechanism for controlling the operation of said pressure actuated means, and means whereby the air pressure may be utilized independently of said thermostatic mechanism for shutting off inflow to one of said units.

5. The combination with a railway car provided with a source of supply of air under pressure, of a heating system comprising a plurality of radiating units, pressure actuated means for closing said units against the admission of heating medium, thermostatic mechanism for controlling the operation of said pressure actuated means, and means operable to release one of said pressure actuated means from the thermostatic control whereby the admission of heating medium to said units may be automatically controlled or one unit so controlled and the other closed against the admission of heating medium.

6. The combination with a railway car provided with a source of supply of air under pressure, of a heating system comprising a plurality of radiating units provided severally with inlet valves which normally stand open, pressure actuated devices for closing said valves, a thermostatically controlled air valve for governing the application of air pressure to said pressure actuated devices, and a radiation valve whereby the pressure may be applied to the pressure actuated device of one of said radiator valves irrespective of the position of the air valve.

45 7. The combination with a railway car provided with a source of supply of air under pressure, of a heating system comprising radiating units provided severally with inlet valves which normally stand open, pressure actuated devices for closing said valves, a thermostatically controlled air valve for governing the application of air pressure to the pressure actuated device of one radiator valve, and a radiation valve which, in one position, admits air pressure to the pressure actuated device of the other radiator valve irrespective of said air valve, and in another position admits the air pressure to said pressure actuated device subject to the control exercised by said air valve.

60 8. The combination with a railway car provided with a source of supply of air under pressure, of a heating system comprising primary and auxiliary radiating units provided severally with inlet valves which

normally stand open, pressure actuated devices for closing said valves, a thermostatically controlled air valve, a pipe leading from the source of supply of air to the air valve, a pipe leading from the air valve to the pressure actuated device of the primary unit, a branch pipe therefrom to the other pressure actuated device, a pipe directly connecting the source of supply with said last named pipe, and a radiation valve adapted, 70 in one position, to direct air pressure to the pressure actuated device of the auxiliary radiating unit irrespective of the air valve, and in another position to subject this pressure actuated device to control by said air valve.

9. A railway car heating system comprising, in combination, a plurality of radiating units connected together so that one is, 85 adapted to receive heating medium discharged from another, thermostatic mechanism capable of being set to operate at different car temperatures for controlling the introduction of heating medium to both of the units to maintain the car at any one of a number of different temperatures, and means whereby one of said units may be closed independently of said thermostatic mechanism.

10. A railway car heating system comprising, in combination, a plurality of radiating units connected together so that one is adapted to receive heating medium discharged from another, thermostatic mechanism capable of being set to operate at different car temperatures for controlling the introduction of heating medium to the units to maintain the car at any one of a number of different temperatures, and means for interrupting and reestablishing said thermostatic control as to one unit and for controlling the closing and reopening of said unit, whereby the reopening of said unit subjects it to the control of said thermostatic mechanism.

11. A railway car heating system comprising, in combination, a primary radiating unit, a thermostatic mechanism capable of controlling the introduction of heating medium to said unit to maintain the car at any one of a number of different temperatures, an auxiliary radiating unit, and means whereby said auxiliary unit may either be closed to the introduction of heating medium or subjected to the control of said thermostatic mechanism.

12. A railway car heating system comprising, in combination, a plurality of radiating units, a plurality of thermostats set to operate at different car temperatures and adapted to be made operative selectively, to maintain the car at any one of a number of different temperatures, and means for controlling the closing of one of said radiating units independently of said thermostatic

control which means permits the reopening of said unit only under control of one of said thermostats.

13. A railway car heating system comprising, in combination, a primary radiating unit, a plurality of thermostats set to operate at different car temperatures and adapted to be made operative, selectively, for maintaining the car at any one of a number of different temperatures, an auxiliary radiating unit, and means whereby said auxiliary unit may either be closed to the introduction of heating medium or subjected to the control of one of said thermostats.

14. The combination with a railway car provided with a source of supply of air under pressure, of a heating system comprising primary and auxiliary radiating units provided with valves to govern the admission of heating medium thereto, which valves normally stand open, air motors to close said valves, an air valve to control the application of air to the motor of the primary unit, a plurality of thermostats set to operate at different car temperatures and adapted to be made effective, selectively, to govern the operation of said air valve, and means whereby the air motor of the auxiliary unit may be subjected directly to air pressure, irrespective of the position of said air valve, or may be put under the control of said air valve.

15. The combination with a railway car provided with a steam train pipe and a compressed air supply pipe, of a heating system for the car comprising a primary radiating unit and a secondary radiating unit, four-way valves associated with said units, respectively, the four-way valve of the primary unit adapted to direct the steam from the train pipe through its unit and then to the other four-way valve or to close its unit and short circuit the steam directly to the other four-way valve, the four-way valve of the auxiliary unit adapted to direct the steam through its unit or to close the same, motors adapted to be actuated by air pressure to close said valves, springs which operate to open the valves, a magnetically actuated air valve for controlling the application of air pressure to the primary unit, a plurality of circuit breaking thermostats arranged in independent circuits and adapted to break their circuits at rise of temperature to different points, a switch for making said thermostats effective, selectively, the magnet of said electro-magnetic air valve being arranged in a circuit of greater resistance than and which is a shunt from said thermostat circuits, and a radiation valve whereby air may be admitted to the air motor of the auxiliary unit independently of said electro-magnetic air valve or under the control of said air valve, as desired.

16. In a railway car heating system, the combination of a radiator, means whereby heating medium may be allowed to pass through said radiator as an entirety or through only a portion of the same, and thermostatic mechanism in the car and subject to the temperature therein for controlling the flow of heating medium through said radiator as a whole if the whole is under steam or through a part of the same if only a part is under steam, to prevent the car temperature in either case from exceeding a certain determined temperature.

17. In a railway car heating system, the combination of a radiator, means whereby heating medium may be allowed to pass through said radiator as an entirety or through only a portion of the same, and electrically actuated mechanism comprising a plurality of circuit making and breaking thermostats in the car and subject to the temperature therein which function at different temperatures for controlling the flow of heating medium whether through said radiator as a whole or through a portion of the same only, and means whereby said thermostats may be put into control of said system selectively.

18. In a railway car heating system, the combination of a radiator comprising two radiating units, means for causing heating medium to pass through one of said units or through both of the same, and thermostatic means for controlling the quantity of heating medium introduced into the unit or units operative whether the heating medium is circulated through one or both of said units to maintain the car at a temperature not in excess of one of a plurality of determinate temperatures selectively determinable.

19. In a car heating system, the combination of a radiator comprising two radiating units, valves to control the inflow of heating medium to said units separately, a motor for operating each of said valves, thermostatic means for controlling the operation of said motors, and means whereby one of said motors may be freed from the control of said thermostatic means without freeing the other motor therefrom.

20. In a railway car heating system, the combination of a radiator comprising a primary unit, thermostatic means responsive to temperature changes in the car atmosphere for controlling the admission of heating medium to said unit, an auxiliary radiating unit subject to said thermostatic control, and means whereby the heating medium may be admitted to or shut off from the auxiliary radiating unit without affecting the thermostatic control of the primary unit.

21. In a railway car heating system, the combination of a radiator comprising a

primary unit, a plurality of thermostats in the car adapted to function at different temperatures for controlling the admission of heating medium to said unit, means for putting any one of said thermostats selectively into control, an auxiliary radiating unit subject to said thermostatic control, and means whereby the heating medium may be admitted to or shut off from the auxiliary radiating unit without affecting the thermostatic control of the primary unit.

HARRY G. GEISSINGER.
